CARBURETOR VALVE CONTROL

Robert M. Callihan, Foley, Fla.

Application May 21, 1934, Serial No. 726,872

7 Claims. (Cl. 192—61)

This invention relates to an automatic carburetor throttle valve control, and has for the primary object the provision of a device which is especially adaptable for motor vehicles where 5 by the driver may control the speed of the vehicle in a conventional manner or may set the device so that the motor vehicle may be automatically maintained at a selected speed under varying loads or when traveling on the level or uphill, 10 relieving the driver of manually governing the speed of the vehicle when desired.

Another object of this invention is the provision of means for rendering the automatic carburetor throttle valve control inoperative during the slowing down or stopping of the vehicle so that the 15 engine may operate at idling speed.

With these and other objects in view this invention consists in certain novel features of construction, combination and arrangement of parts 20 to be hereinafter more fully described and claimed.

For a complete understanding of my invention, reference is to be had to the following description and accompanying drawings, in which 25

Figure 1 is a fragmentary vertical sectional view illustrating a portion of a motor vehicle and its engine with my invention applied thereto.

Figure 2 is a fragmentary vertical sectional view showing my invention connected to the 30 throttle valve of a carburetor of the engine and its connection with the intake manifold of the engine and with the battery or other electrical source of the automobile.

Figure 3 is a sectional view taken on the line 35 3—3 of Figure 2.

Figure 4 is a sectional view taken on the line 4—4 of Figure 2.

Figure 5 is a detail view, partly in section, showing a switch actuated by the depressing of 40 either the clutch or brake pedals of the automobile.

Figure 6 is a front elevation, partly in section, illustrating a resistor control switch mountable upon the steering post or column of the automobile.

Figure 7 is a detail sectional view showing the connection of my invention and the foot accelerator of the automobile to the throttle valve.

Figure 8 is a detail sectional view taken on 50 the line 8—8 of Figure 7.

Referring in detail to the drawings, the numeral 1 indicates a fragmentary portion of an automobile, the engine thereof being indicated by the character 2. My invention, indicated by the 55 numeral 3, in entirety is mounted in any suitable

manner to the automobile adjacent the engine and preferably near the carburetor 4 of the engine. The carburetor has the usual throttle valve 5 for controlling the fuel to the engine and consequently controlling the speed of the 5 engine. The stem of the valve is indicated by the character 6 and has secured thereto a sleeve 7 on which is formed an arm 8 to be connected to my invention by a rod or link 9. The sleeve 7 rotatably receives a shaft 10 forming part of 10 the usual foot accelerator 11 of the automobile. A pin 12 is carried by the shaft 10 and operates in a slot 13 in said sleeve 7 so that the position of the throttle valve 5 may be varied by the foot 15 accelerator. The pin and slot arrangement permits operation of the valve 5 by my invention without effecting or moving the foot accelerator and also permits the manual control of the carburetor by the accelerator when desired.

The device indicated by the character 3 consists of a solenoid 14 having a slidable core 15 working against the action of the coil spring 16, the tension of which may be varied through the adjustment of a bushing or sleeve 17. The core 15 has a pin and slot connection with an arm 18 25 of a bell crank lever 19, the latter being pivoted to a support 20 carried by the casing of the solenoid. The arm 21 of the bell crank lever 19 is pivoted to the rod or link 9 thereby establishing an operative connection between the core 30 of the solenoid and the throttle valve 5.

Removably secured to the casing of the solenoid is a cylinder 22 in which is slidably mounted a piston 23, the stem 24 thereof being suitably connected to the core 15 by extending through a 35 packing gland 25 and the bushing or sleeve 17. The connection between the cylinder 22 and the casing of the solenoid is by spaced arms 26 which will permit a person to readily turn the sleeve or bushing 17 for varying the tension of the 40 spring 16. A removable head 27 is provided for the cylinder 22 and has a vent opening 28. A pipe 29 is connected to the cylinder and to the intake manifold 30 of the engine 2. The cylinder 45 forms a vacuum chamber and the vacuum is established by the operation of the engine from the intake manifold and the vacuum acts upon the piston 23 to urge the throttle valve in the direction towards a closed position while the energization of the electro-magnet acts to urge 50 the valve towards an open position.

The solenoid 14 includes a potential winding 31 and a current winding 32. The potential winding and the current winding are connected to a ground 33 by a conductor 34. The current 55

winding is connected to a switch 35 located adjacent the clutch and brake pedals 36' and 37' of the motor vehicle and the switch 35 is connected to a resistor control switch 36 by a conductor 37. The switch 36 is preferably mounted upon a steering column 38 of the motor vehicle so that it can be conveniently operated by the driver. The switch 36 is connected to a switch 39 mounted on the instrument board of the motor vehicle and is of the manually actuated type, the connection between the switches 36 and 39 being by way of a conductor 40. The switch 39 is connected to a battery 41 of the motor vehicle. A conductor 42 is connected to the dead side of the switch 39 and to the potential winding of the solenoid. The switch 36 is equipped with a finger piece 43 having an indicator 44 movable over a dial 45. The dial is graduated and supplied with characters to indicate miles per hour so that by setting the indicator on the scale on the dial to a selected mile per hour the core 15 will be drawn into the solenoid against the resistance of the spring 16 a certain amount for the opening of the throttle valve to maintain the operation of the engine at the selected speed for the motor vehicle. The load variances on the engine due to the vehicle traveling on level and uphill will affect the vacuum developed in the cylinder 22 so that as the load decreases the vacuum increases for permitting the throttle valve to open a greater extent for maintaining the operation of the engine at the selected rate of speed.

The depressing of either the clutch or foot pedal for the purpose of retarding or stopping the motor vehicle, the switch 35 will be actuated to interrupt the circuit to the current winding of the solenoid, consequently permitting the vacuum and spring 16 to act to move the throttle valve to a position for maintaining the engine operating at idling speed. The potential winding of the solenoid is still energized during the opening of the switch 35 for the purpose of retaining the solenoid core in a central position and excited ready to move with the slightest change in current flow. When desiring to render the automatic control of the throttle valve inoperative the driver opens the switch 39 and the speed of the engine then may be manually controlled through the actuation of the foot accelerator 11.

The switch 35 includes in its construction an arm 46 underlying the clutch and brake pedals of the automobile and normally maintained in engagement therewith by a spring 47 so that a depressed movement of either of the pedals will effect the opening of the circuit to the current winding of the solenoid for the purpose heretofore described.

Having described the invention, I claim:

1. An automatic carburetor throttle valve control including an engine having an intake manifold and a control valve therefor and an electric circuit, electrical means connected to the electric circuit and to the throttle valve for opening said valve, and vacuum means connected to and acting in opposition to the electrical means and connected to the intake manifold for moving said valve towards closed position and responsive to the degree of vacuum in the intake manifold to determine the opening movement imparted to the valve by said electrical means.
2. An automatic carburetor throttle valve control including an engine having an intake manifold and a control valve therefor and an electric circuit, electrical means connected to the electric circuit and to the throttle valve, manually con-

trolled means in said circuit for actuating said electrical means for opening the valve, and vacuum means connected to and acting in opposition to the electrical means and connected to the intake manifold for moving said valve towards closed position and responsive to the degree of vacuum in the intake manifold to determine the opening movement imparted to the valve by said electrical means.

3. An automatic carburetor throttle valve control including an engine having an intake manifold and a control valve therefor and an electric circuit, a solenoid electrically connected to said electric circuit and having a core, means for connecting the core to the throttle valve, spring means acting against the core in opposition to the movement of the core by the energization of the solenoid, means in said electric circuit for varying the action of the solenoid upon the core for opening the valve, and a vacuum means connected to the core and to the intake manifold for moving said valve towards closed position and responsive to the degree of vacuum in the intake manifold to determine the opening movement imparted to the valve by said solenoid.

4. An automatic carburetor throttle valve control including an engine having an intake manifold and a control valve therefor and an electric circuit, a solenoid electrically connected to said electric circuit and having a core, means for connecting the core to the throttle valve, spring means acting against the core in opposition to the movement of the core by the energization of the solenoid, means in said electric circuit for varying the action of the solenoid upon the core for opening the valve, a vacuum means connected to the core and to the intake manifold for moving said valve towards closed position and responsive to the degree of vacuum in the intake manifold to determine the opening movement imparted to the valve by said solenoid, and means in said electric circuit for breaking the latter to render said solenoid inoperative.

5. An automatic carburetor throttle valve control including an engine having an intake manifold and a control valve therefor and an electric circuit, electrical means connected in the electric circuit and to the throttle valve for opening said valve, a vacuum cylinder connected to the intake manifold, and a piston operating in said cylinder and connected to said electrical means and acting in opposition to the latter by the vacuum in said cylinder for moving said valve towards closed position and responsive to the degree of vacuum in the intake manifold to determine the opening movement imparted to said valve by the electrical means.

6. In combination with a motor vehicle provided with clutch and brake pedals and an engine having an intake manifold and a control valve actuated by an accelerator, an electric circuit, a solenoid electrically connected to said electric circuit and having a core, means connecting said core to the control valve, spring means engaging the core to urge the control valve towards closed position, a manually controlled means in said circuit for varying the action of the solenoid upon the core for opening the valve, and vacuum means connected to the intake manifold and to the core for moving said valve towards closed position and responsive to the degree of vacuum in the intake manifold to determine the opening movement imparted to the valve by the solenoid, means in said circuit and actuated by the movement of either the

brake or clutch pedal for breaking said circuit and permitting operation of the control valve by the accelerator.

7. In combination with a motor vehicle provided with clutch and brake pedals and an engine having an intake manifold and a control valve actuated by an accelerator, an electric circuit, a solenoid electrically connected to said electric circuit and having a core, means connecting said core to the control valve, spring means engaging the core to urge the control valve towards closed position, a manually controlled means in said circuit for varying the action of the solenoid upon the core for opening the valve, vacuum means connected to the intake

manifold and to the core for moving said valve towards closed position and responsive to the degree of vacuum in the intake manifold to determine the opening movement imparted to the valve by the solenoid, means in said circuit and actuated by the movement of either the brake or clutch pedal for breaking said circuit and permitting operation of the control valve by the accelerator, and a secondary circuit for the solenoid to maintain the core in a position for holding the throttle valve partially open to maintain the engine operating at idling speed when the first-named circuit is broken. 5 10 15
